3 Claims

ABSTRACT OF THE DISCLOSURE

A method of treating patients with hepatic encephalopathy which comprises administering daily to said patients a small but effective amount of sorbitol.

This invention relates to a method of treating patients suffering from hepatic encephalopathy.

Chronic portal-systemic (hepatic) encephalopathy, sometimes referred to as "hepatic coma," is an incapacitating disease, and in many patients control of neuro-psychiatric symptoms remains unsatisfactory. Present treatment is aimed at reduction of ammonia and other nitrogenous compounds produced in the large bowel from protein derivatives by bacterial degradation. Long term restriction of dietary proteins, one method of treatment, is not effective as it exaggerates an already existing negative nitrogen balance. Reduction of bacterial flora by long-continued administration of neomycin may be complicated by diarrhea, steatorrhea, moniliasis and staphylococcal enterocolitis. Purgation has only a slight effect and its use is limited to very mild cases. Colectomy or surgical exclusion of the colon has an operative mortality of up to 50%. Therefore, it can be seen that present methods of treating this disease have not been very successful.

It has now been found that the condition of patients suffering from hepatic encephalopathy may be markedly improved by orally administering to said patient a daily dosage of an effective amount of sorbitol. The sorbitol which may be effectively employed for the purposes of this invention is Sorbitol U.S.P. and orally administerable compositions thereof, for example, Sorbitol Solution, U.S.P.

It has been found that the amount of sorbitol which must be administered daily to the patient sought to be treated hereunder is critical. Usually, in practice, the daily dosage of sorbitol which may satisfactorily be employed in the practice of this invention will depend on the formulation employed and the patient being treated, and should be sufficient to daily produce about two watery stools in said patient, the specific dosage being adjusted according to the patient being treated. It has been found that in certain patients, daily administration of 20 grams or more of sorbitol has been effective. In those instances wherein the sorbitol is employed in the form of Sorbitol Solution, U.S.P., from 30 to 180 ml. of said Sorbitol Solution, U.S.P. administered daily has been found to be effective. Preferably, from 60 to 120 ml. of Sorbitol Solution, U.S.P. gives beneficial results although the other amounts are also satisfactory.

The invention may be further illustrated by the following examples.

EXAMPLE 1

G. O. is a 62 year old male having a background of post-necrotic cirrhosis, inactive complicated by ascites and GI bleeding. A portacaval shunt was performed in 1963 and he experienced a few transient episodes of encephalopathy in the next two years. In 1964 he began to develop a tremor of his left hand, then left side. He noted increased

fatigability of his legs, left>right and developed a staggering gait. These symptoms slowly progressed and he has been unable to walk without assistance for over a year now. These findings have been considered to be due to 5 cerebral degeneration related to his chronic liver disorder. In January 1967, he stopped eating meat, eggs, and subsisted mainly on potato soup, fruit, toast, jelly, butter. While on the low protein intake, he felt he was more alert, his tremor decreased and he could maneuver better. 10 At the beginning of March, he began to eat a thin slice of meat each evening. By the 23rd of March he had changed in that he tended to be disagreeable, his comprehension worsened, he started to grimace and developed asterixis. Protein intake was decreased to less than 20 15 grams per day. When symptoms worsened on this regimen he was admitted to the hospital on Apr. 6, 1967.

The patient was placed on Sorbitol Solution, U.S.P., 90 ml./day. Protein intake was increased to 45 grams/day and was well tolerated. He has had 3 brief episodes of 20 drowsiness, incoordination in recent months. These usually occur when his stool number decreases from 2-4 to 1 or less/day. In each instance, decreased protein intake for 1 to 1½ days is sufficient to lead to rapid improvement. On August 24, Sorbitol Solution, U.S.P. therapy was 25 stopped and replaced by milk of magnesia, sufficient to maintain 3-4 stools/day. After 2 days he was felt to be drowsy and less well coordinated. Protein intake was decreased, Sorbitol Solution, U.S.P. therapy was restarted and he returned to his usual state. The patient is currently 30 on Sorbitol Solution, U.S.P., 120 ml./day and eating about 35 to 40 grams of protein per day.

EXAMPLE 2

C. S. M., a 45-year-old white male was admitted to a 35 Louisiana Hospital in December 1964 with an upper GI hemorrhage. A diagnosis of cirrhosis and bleeding esophageal varices was made at that time. He had an enlarged liver and spleen and was noted to have marked weakness of his legs. There was a history of alcoholism but no 40 alcohol ingestion since 1964.

In February 1965 the patient was admitted for the first time to the Dallas VA Hospital because of melena. At that time a right upper lobe lesion was noted in the lungs, and active tuberculosis was established. On Apr. 22, 1965, a 45 side-to-side portacaval shunt, cholecystectomy and liver biopsy were performed. The biopsy diagnosis was Laennec's cirrhosis. Cholelithiasis was present at operation. The patient continued in the hospital until Dec. 2, 1965, when his tuberculosis was considered to be inactive. During 50 his hospitalization he had one or more episodes of lethargy and asterixis, responding to decreasing his protein intake. He was discharged on INH and Pyridoxine.

The patient was again admitted to the Dallas VA Hospital on Oct. 16, 1966 in hepatic pre-coma. Asterixis was 55 present and the EEG was markedly abnormal, suggestive of hepatic coma. The patient responded to routine treatment for hepatic coma, and was discharged on a 70 gram protein diet, and no medications, on October 28, 1966.

On Nov. 16, 1966, the patient was readmitted, in pre-coma with asterixis. At that time he was on a 70 gram protein diet and no medications at home. He responded well to 30 gram protein diet with no other medications. He was discharged on a 30 gram protein diet on Nov. 29, 1966.

60 His next admission to the Dallas VA Hospital was 65 on Mar. 20, 1967, in an attempt to determine the patient's protein tolerance. On admission the EEG was markedly abnormal, and asterixis was present. On neomycin, 4 grams per day, the dietary protein was gradually raised to 70 70 grams, with lowering of the blood ammonia, and improvement in the EEG. Asterixis disappeared, and the patient was alert and oriented. Liver function tests were

stable. Sorbitol Solution, U.S.P., 90 ml. per day, was begun. This had to be decreased to 60 ml. per day because of diarrhea, and was continued through June 11, 1967. Clinical status did not change significantly during this period of time. However, immediately after stopping the Sorbitol Solution, U.S.P., the patient became lethargic, developed asterixis, and on June 14, 1967, the EEG was markedly abnormal. At this point, the protein in the diet was lowered to 50 grams for four days, and Sorbitol Solution, U.S.P. again begun in a dose of 75 ml. per day. Marked clinical improvement, as well as improvement of the EEG, was noted and sustained while the patient was on Sorbitol Solution, U.S.P. which was continued through July 26. On July 26 the Sorbitol Solution was discontinued. During the second week the patient became nervous and lethargic, and the protein intake was voluntarily diminished by the patient at home. On Sept. 1, Sorbitol Solution, U.S.P., 75 ml. per day, was again begun and the patient is to be seen in two weeks and evaluated.

EXAMPLE 3

H. M., a 44 year old male, is a chronic alcoholic. A diagnosis of cirrhosis was made in 1958. He was first admitted to Parkland Memorial Hospital in February 1966 with gastrointestinal bleeding. During this admission, he was in hepatic coma and developed ascites. A second episode of GI bleeding and transient coma ensued in March 1966. He was admitted to the hospital again in May 1966 because of increasing ascites and responded to medical therapy. An elective portacaval shunt was performed on June 20, 1966, and the patient was discharged from the hospital on June 27, 1966.

In September 1966, he was admitted again because of progressive confusion. His course was complicated by heart failure, pseudomonas pneumonia and intermittent coma. He was discharged from the hospital on a 40 gram protein diet, but was readmitted after two days at a nursing home. The patient had been on the 40 gram protein diet for three days prior to discharge.

After readmission in coma on Nov. 23, 1966, with neomycin and adjustment of protein intake, he was alert and oriented by Dec. 5. Neomycin was decreased to 2 grams per day on Dec. 7. Protein intake was gradually increased to 40 grams per day. After three days on this amount of protein he became confused, protein intake was stopped and he gradually improved over the next few days. On Jan. 31, Sorbitol Solution, U.S.P., 90 to 120 ml. daily was instituted and the patient maintained his good clinical state during the nine days of Sorbitol Solution intake. Sorbitol Solution, U.S.P., was then stopped, and after five (5) days a flap was noted, on the sixth day he became confused, disoriented but not comatose.

What is claimed is:

1. A method of treating hepatic encephalopathy which comprises orally administering to patients suffering from said disease a daily dosage of at least twenty grams of sorbitol.
2. The method of claim 1, wherein the sorbitol is Sorbitol Solution, U.S.P.
3. The method of claim 1, wherein the sorbitol is Sorbitol Solution, U.S.P. in an amount of from 30 to 180 ml.
